UNITED STATES PATENT OFFICE.

CHARLES A. BAILEY, OF CROMWELL, CONNECTICUT.

MACHINE FOR MAKING PAPER TUBES.

SPECIFICATION forming part of Letters Patent No. 659,599, dated October 9, 1900.

Application filed July 7, 1900. Serial No. 22,869. (No model.)

To all whom it may concern:

Be it known that I, CHARLES A. BAILEY, a citizen of the United States of America, residing at Cromwell, in the county of Middlesex and State of Connecticut, have invented new and useful Improvements in Machines for Making Paper Tubes, of which the following is a specification.

This invention is an improvement in machines for making paper tubes employed in the manufacture of paper-tube cartridges; and the object of the said invention is to construct a machine of this character that shall be entirely automatic in its operation, feeding the paper to an arbor upon which it is tightly wound and the thicknesses pasted together, cutting the paper when the required thickness of tube is had, and then stripping the completed tube from the arbor.

The invention also includes the idea of lapping the paper upon the arbor to insure its proper engagement therewith in starting the tube and makes provision for removing the surplus paste from the finished tube as it is ejected from the machine, and, furthermore, it provides for changing the size of the arbor, whereby the tube is more easily removed therefrom.

With the above objects in view the invention consists, as a whole, of an arbor supported in vertical movable bearing, a paste-pot into which the arbor is lowered, gearing by which said arbor is revolved when at its lowermost position, mechanism for feeding a continuous sheet of paper to the arbor and cutting said paper at intervals, a device for lapping the paper upon the arbor to insure its proper engagement therewith, a stripper adapted to push the finished tube from the arbor, and a wiper for cleaning the surplus paste from said tube as it passes from the machine, all as hereinafter fully described in the following specification, and more particularly set forth in the appended claims.

The invention also consists in novel combination of parts and special features of construction embodied in the machine.

In the accompanying drawings, which form a part of this specification, and in which like letters of reference indicate like parts throughout the several views, Figure 1 is an end elevation of a tube-making machine constructed

in accordance with my invention. Fig. 2 is a front elevation of the machine proper, the paper-roll and its supporting-frame being removed. Fig. 3 is a front elevation of the main part of the machine removed from the supporting-frame, a part being broken away to show the gearing which operates the stripper. Fig. 4 is a vertical sectional view on the line 4-4 of Fig. 3. Fig. 5 is a vertical sectional view on the line 5-5 of Fig. 3. Fig. 6 is a detail longitudinal sectional view of the winding-arbor and its movable support. Fig. 7 is a detail sectional view of the winding-arbor. Fig. 8 is a detail sectional view of the paper-cutting rolls.

The mechanism of the machine is supported by a frame consisting of castings or end pieces A A, which are connected together near their lower ends by tie-rods a a and are braced at their upper ends by the shafts and parts which they support, the said end pieces providing integral bearing-boxes a' a', in which is journaled a horizontal shaft B, carrying the operating cam-wheel, hereinafter described.

C designates a frame or casting which is mounted upon the end pieces A A and forms practically the top of the supporting-frame of the machine, the upper part of said frame presenting a receptacle or pan C', which holds the paste that is applied to the paper as it is wound upon the arbor in forming the tube. The paper is guided into position below the arbor by means of a guide-plate c, which extends over the front wall of the receptacle or paste-pan, down the inner side thereof, and is curved upward at its lower end, as shown in Fig. 5. The curved lower end of the plate c serves to press the paper against the arbor, so that it will be readily caught and wound thereon.

Slidably mounted in a casing A', bolted to the forward end of the machine, is a vertical plate A², forming the movable support for the arbor D, and for the purpose of providing a steady support for said arbor the plate carries a long tubular bearing a², Fig. 6, in which the stem of the arbor is mounted. The outer end of the stem projects beyond the tubular bearing, and made fast to said projecting end is a pinion D^X, by which the arbor is turned, and which pinion is brought into

mesh with the driving mechanism only when the arbor is lowered into the paste-pan to wind the paper thereon. The arbor is hollow throughout its length, and that part of the 5 same upon which the paper is wound is split (see Figs. 6 and 7) in order that it may be expanded laterally to form a paper tube of a certain diameter and then contracted to permit said tube to be more easily pushed 10 therefrom by the stripper or ejector, herein-after described. The arbor is therefore made of spring-steel, and the split portion is contracted in its normal condition and is expanded by means of a flat strip D', having a 15 stem located in the stem of the arbor, one part being provided with a spiral groove d, engaging a screw d' of the other part, so that when the expander D' is moved longitudinally in the arbor it will be turned independently thereof and spread the bifurcated portions of said arbor. To provide for moving said expander, the projecting outer end thereof has a swivel d² with arms d³, the latter extending into an irregular slot e in the depending 20 members e' e' of a bracket E, supported at the ends of guide-rods f f, and said projecting end of the expander is supported by slotted arms d⁴, carried by the tubular bearing a². It will be observed that the bracket 25 E is stationary and that the slot e is disposed at such an angle that when the arbor and spreader are lowered by their supporting-frame the said spreader will be pushed inward; also, that the spiral groove d and screw d' are so arranged that upon an inward movement of the spreader the latter will be given a quarter-turn, bringing the ends of the flat portion of said spreader to bear against the bifurcated portions of the arbor, thereby 30 separating them and increasing the diameter of that portion of the arbor, and, furthermore, that the disposition of said slot is such that the arbor will be expanded when at its lowermost position and contracted when 35 raised to its uppermost position. Rubber strips d⁵ are let into the sides of the arbor to form surfaces which will better adhere or catch the paper and start it upon the arbor.

The plate A², forming the movable support 40 for the arbor, is raised and lowered by a pinion g, meshing with rack-teeth a⁸ on said plate, the pinion being turned by a slide G, having a set of rack-teeth g', in mesh with a pinion g², mounted on the same shaft as the 45 pinion g, said shaft g³ being journaled in a housing a⁵, bolted to the casing A', as shown in Fig. 3. The slide G extends longitudinally of the machine, being located in the upper part of a groove or channel c' in the under 50 side of the frame C, and passes through the casing A' and housing a⁵. The other end of said slide-bar G is provided with a set of rack-teeth g⁴, in mesh with a pinion g⁵ on a shaft g⁶, carrying also a pinion g⁷, meshing with a 55 rack a⁶, formed on a vertical slide-plate A³. The shaft g⁶ is supported in a housing a⁷, similar to housing a⁵ at the other end of the

machine, and the plate A³ has a vertical movement in a casing a⁸, bolted to the frame or casting C. The plate A³ is provided for 70 the purpose of carrying a device or arm H, which is moved into engagement with the free end of the arbor D when it is lowered to prevent an upward movement of the free end of the arbor as the paper is wound thereon and is moved out of engagement with said arbor when in its uppermost position to permit the tube to be pushed therefrom. It is obvious, therefore, that the movable supporting-plate A³ should have a greater movement 75 than the supporting-plate A², which carries the arbor, and this is provided for by having the pinion g⁵, which meshes with the slide G, smaller than the pinion g⁷, which meshes with the vertical rack, while the pinions g² and g⁴ for raising and lowering the vertical plate or support A² are of the same size as pinion g⁵. It will be observed also that as both supporting-plates A² and A³ are raised and lowered in unison the rack-teeth at the 80 ends of the slide G are at opposite sides of said slide and engage the upper part of the pinion at one end of the machine and the lower part of the pinion at the other end of the machine. The slide G is moved by a 85 cam-wheel I, provided with a rib i, engaging a depending lug g⁹, secured to the under side of said slide.

J designates the stripper or tube-ejector, consisting of a sleeve adapted to slide upon the arbor and push the tube therefrom, the said sleeve having circumferential flanges forming a groove, into which fits a depending bifurcated portion k of a slide K, the latter being slidably mounted upon the guide-rods 105 f f, hereinbefore referred to, said rods being supported in brackets a⁹ and a¹⁰, bolted upon opposite ends of the frame C. The slide K is operated by a slide-bar L, secured thereto and extending therefrom through the brackets a⁹ and E, by which it is supported, the said slide-bar having a set of rack-teeth on 110 its outer side, which teeth are in mesh with a pinion M, fast to the upper end of a vertical shaft m, supported in a suitable bracket 115 a¹¹, the said shaft being turned by a pinion M', fast to its lower end, being in mesh with a large gear-wheel N on a shaft n, having a pinion N', in mesh with the rack-teeth of a 120 slide O, mounted in the frame below the slide G, and having a depending lug o, engaged by a rib i' on the cam-wheel I. It will be observed, therefore, that a movement of the slide O back and forth will reciprocate the slide-bar L through the intervention of the 125 gearing hereinbefore described, and said slide-bar carrying the slide K, which is in engagement with the tube-ejector J, will reciprocate said tube-ejector to push the tube from the arbor; also, that the interposed large gear-wheel N provides for the movement of the tube-ejector the entire length of the arbor, and, further, that the gearing of the parts is 130 such that the slide which operates the tube-

ejector does not commence to reciprocate until the arbor is moved to the limit of its upward movement.

The bracket a^{10} is provided with an opening through which the tube passes as it is ejected from the machine, said opening being on a line with the upper position of the arbor, and at the inner end of this opening is a tubular projection p , supporting a flexible washer or wiper P , held in place by a flanged ring p' , screwed onto the said tubular projection. This washer or wiper is of little less diameter than the tube, and as said tube passes through the same will scrape the surplus paste therefrom. It will be understood, of course, that the slide A^3 is provided with an opening on a line with the opening through the bracket a^{10} to permit the finished tube to pass therethrough, and, if desired, a trough may be provided to receive the tube as it passes from the machine and deposit it into a basket or other receptacle.

Q designates the driving-shaft of the machine, on which is the band-pulley Q' , said shaft being journaled at its inner end in a box a^{12} , formed integrally with one of the end pieces A , and at its outer end is journaled in a cross-bar Q^2 , supported by rods q , projecting from said end piece. This driving-shaft has a gear-wheel R mounted thereon in vertical line with the pinion D^X at the outer end of the arbor and so located that said pinion will mesh therewith when the arbor is in its lowermost position, for it is only necessary that the arbor be revolved during the winding of the paper thereon. Said driving-shaft also carries a pinion Q^3 , in mesh with a large gear-wheel B' on shaft B , upon which the cam-wheel I is mounted. The driving-shaft also has a band-pulley Q^4 , by which to drive the paper-feeding mechanism hereinafter described.

In feeding the paper to the machine, either separate sheets by hand or a continuous sheet by way of the feeding mechanism, it is passed under the arbor a sufficient distance, so that when said arbor descends it will push it down into the guide-plate or curved former c and into the paste, and in order to insure the proper engagement of the paper with the arbor it is folded over upon the same by a swinging plate S , which is pivoted at its ends in blocks s , secured to the bottom of the paste-pan, and is operated by a lever S' , pivoted in a bracket c^5 , secured to the rear end of the frame C and connected to said plate by a connecting-rod s' and arm s^2 . (See Figs. 4 and 5.) As the paper is folded over upon the arbor by means of the pivoted plate S said paper is creased, and, if found necessary, an elevated trough may be provided to feed a supply of paste between the thicknesses of the fold. The pivoted lever S' is operated by a lug i^2 on the cam-wheel I engaging the foot of said lever.

The paper-feeding mechanism is supported in brackets T T , having tongues t at their

lower ends engaging corresponding grooves in the upper ends of the end pieces A A of the main supporting-frame of the machine. 70

In these brackets are mounted a pair of paper-cutting rolls U and U' , one above the other, said paper-cutting rolls being preferably covered with felt or other soft material to give the required friction and insure the proper feeding 75 of the paper. The shafts or gudgeons at one end of the cutting-rolls extend beyond the bracket and carry pinions u and u' , in mesh with each other, the gudgeon of the lower roll U' being farther extended to receive a band-wheel u^2 , over which passes a belt from the band-pulley Q^4 on the driving-shaft. The paper (lettered V) is inserted between the feed-rolls and the roll of paper supported in a suitable frame, Fig. 1. As the paper is 80 not fed continuously to the machine, means are provided for stopping the paper-cutting rolls and releasing them, consisting of a dog w , adapted to engage a recess in the lower roll and operated from the cam-wheel I by 85 means of an arm w' , fast to a shaft W , to which said dog is also made fast. Lug i^2 strikes arm w' to operate the shaft W , and said shaft is journaled at its ends in frames T . The paper is cut into the proper lengths 90 by the rolls U and U' , one having a longitudinal cutting-blade and the other a recess or groove into which the blade forces the paper and cuts it. By providing the groove the rolls retain a hold upon the paper. Tension on 100 the paper is provided for by intermediate guide-rolls Y and Y' , supported in end frames and normally separated by springs y to permit the paper to readily pass between them and are brought together by arms Y^2 , depending from the slides A^2 and A^3 and engaging the extended ends of the shaft of the upper roll. Guide-rolls z are interposed between the paper-roll V' and cutting-rolls. 105

From the foregoing description, in connection with the accompanying drawings, the construction and operation of my invention will be apparent to those skilled in the art to which it applies, for, assuming that the parts are in the initial position, as shown in 110 the drawings, the feeding mechanism operates to feed the paper under the raised arbor. The slide G is then moved to operate the mechanisms at the ends of the machine, which lower the arbor and press the arm H against 115 the free end thereof, said arbor carrying the paper with it down into the paste and upon the curved former c , while the pivoted plate S operates simultaneously to fold the end of the paper upon the arbor. As said arbor is 120 lowered the split portion thereof is expanded by the spreader and reaching its lowermost position the pinion D^X comes into mesh with the gear-wheel R , which rapidly revolves the arbor, causing the paper to be wound 125 thereon, the paste being supplied by reason of the arbor being partly submerged therein. As soon as the paper has been wound upon the arbor, thereby forming the tube, 130

the said arbor is then raised by the interposed mechanism, and the stripper J coming into engagement with the slide K the latter is moved forward to push the tube from the 5 arbor and is then returned to its normal position, this operation of the slide being effected by the slide-bar O, which actuates the gearing that revolves the pinion M, which is in mesh with the rack-bar L, secured to said 10 slide. This operation is repeated in forming a second tube, and so on.

The machine is adapted to form a very long tube, and therefore the free end of the arbor upon which the tube is formed is steadied by 15 means of the depending arm H, which is brought into engagement with said free end when the arbor is lowered and is moved out of engagement when the arbor is raised, as hereinbefore described, so as not to interfere 20 with the removal of the tube by the ejector.

As heretofore suggested, paper sheets of the required size can be fed into the machine singly by hand in lieu of using a continuous sheet and the mechanism hereinbefore described for feeding said sheet and cutting it. 25 In case individual sheets are employed said sheets could be supplied with paste before their introduction into the machine.

The split arbor in connection with the rotatable core or spreader provides for expanding and contracting said arbor to facilitate the removal of the finished tube, as hereinbefore stated, and though I prefer to use this particular arbor in the machine it is evident 35 that a solid arbor will answer the purpose, especially if said solid arbor is triangular or polygonal in cross-section. It is also obvious that the gearing mechanism for actuating the several instrumentalities could be changed 40 without departing from the spirit of my invention, for other well-known mechanical contrivances could be employed for raising and lowering the arbor, reciprocating the stripper or tube-ejector, and actuating the automatic paper-feeding mechanism.

The machine constructed in the manner herein shown and described provides for performing the different functions automatically, and as all the parts are positive in action 50 the machine will really require no attention whatever other than to supply the paste and paper.

Having thus described my invention, what I claim as new, and desire to secure by Letters 55 Patent, is—

1. In a machine for making paper tubes, the combination, of a paste-supply, a reciprocating arbor, and means for revolving said arbor.
2. In a machine for making paper tubes, the combination, of a paste-supply, an arbor reciprocating laterally, and means for revolving said arbor intermittently, substantially as shown and described.
3. In a machine for making paper tubes, the combination, of a paste-supply, an arbor reciprocating laterally, and means for revolv-

ing said arbor when it is at the limit of its movement in one direction, substantially as shown and described.

4. In a machine for making paper tubes, the combination, of a paste-supply, and a revoluble arbor, one having a reciprocating motion laterally to and from the other, substantially as described.

5. In a machine for making paper tubes, the combination, of a revolving arbor upon which the paper is wound, a reciprocating stripper or tube-ejector adapted to remove the tube from the arbor, and a wiper through 80 which the tube passes.

6. In a machine for making paper tubes, the combination, of a revolving arbor upon which the tube is wound, a reciprocating stripper or tube-ejector adapted to remove the tube 85 from the arbor, and a rubber ring or gasket through which the tube passes, substantially as shown and described.

7. In a machine for making paper tubes, the combination, of a paste-pot, a revolving 90 arbor movable vertically in and out of said paste-pot, and means for removing the tube from the arbor, substantially as shown and described.

8. In a machine for making paper tubes, 95 the combination, of a paste-pan, an arbor movable vertically into and out of said pan, and a sleeve adapted to reciprocate upon the arbor to remove the tube therefrom.

9. In a machine for making paper tubes, 100 the combination, of a paste-pan, a vertically-movable arbor, means for revolving said arbor when it is lowered into said pan, and means for removing the finished tube when the arbor is raised, substantially as shown and 105 described.

10. In a machine for making paper tubes, the combination, of a paste-pan, an arbor movable into and out of said pan, means for revolving the arbor when lowered into the pan, 110 and means for removing the finished tube when the arbor is raised, substantially as shown and described.

11. In a machine for making paper tubes, 115 the combination, of a paste-supply, an arbor movable to and from the same, means for revolving the arbor, and means for removing the finished tube, substantially as shown and described.

12. In a machine for making paper tubes, 120 the combination, of a paste pan or receptacle containing paste, a revolving arbor movable into and out of the paste, a pivoted plate adapted to fold the paper upon the arbor, and means for removing the finished tube, substantially as shown and described.

13. In a machine for making paper tubes, 125 the combination, of a pan or receptacle containing paste, a revolving arbor movable into and out of the paste, a device for folding the 130 end of the paper upon the arbor, and means for removing the finished tube, substantially as shown and described.

14. In a machine for making paper tubes,

the combination, of a pan or receptacle containing paste, an arbor movable into and out of the paste, means for revolving the arbor, a device for folding the paper upon the arbor, means for removing the finished tube from the arbor, and a wiper through which the tube passes, substantially as shown and described.

15. In a machine for making paper tubes, the combination, of a pan or receptacle containing paste, an arbor movable into and out of the paste, means for revolving the arbor, mechanism for feeding paper under the arbor, and a tube-ejector for removing the finished tube, substantially as shown and described.

16. In a machine for making paper tubes, the combination, of a vertically-movable arbor, a swinging plate adapted to fold the paper upon the arbor, and means for removing the finished tube, substantially as shown and described.

17. In a machine for making paper tubes, the combination, of a revoluble arbor having a reciprocating motion in the machine, a pan into which the arbor reciprocates, and a swinging plate adapted to fold the paper upon the arbor, substantially as shown and described.

18. In a machine for making paper tubes, the combination, of a revoluble arbor movable in the machine, a pan or receptacle into which the arbor moves, mechanism for feeding the paper under the arbor, a swinging plate folding the paper upon the arbor, and a tube-ejector slidably upon the arbor, substantially as shown and for the purpose set forth.

19. In a machine for making paper tubes, the combination, of a revoluble arbor movable in the machine, a pan for holding paste, mechanism for feeding the paper under the arbor, a swinging plate adapted to fold the paper upon the arbor, a tube-ejector slidable upon the arbor, and a wiper through which the arbor passes from the machine, substantially as shown and described.

20. In a machine for making paper tubes, the combination, of a revoluble arbor movable in the machine, a pan for holding paste, feeding-rolls between which the paper is fed to the arbor, and a knife carried by one of said rolls; together with a tube-ejector slidably upon the arbor, substantially as shown and described.

21. In a machine for making paper tubes, the combination, of a revoluble arbor reciprocating laterally in the machine, a pan for holding paste into which the arbor moves, a folder, a tube-ejector, and a wiper, substantially as shown and described.

22. An arbor for a tube-making machine, comprising a hollow tube split longitudinally, and a flat strip rotatable within said tube.

23. An arbor for a tube-making machine, comprising a hollow tube split longitudinally, rubber strips let into the sides of the tube, and a flat strip rotatable in said arbor.

24. An arbor for a paper-tube-making machine, comprising a tube split longitudinally, and a spreader for expanding said tube laterally; combined with a sleeve slidable upon the tube, substantially as shown and described.

25. An arbor for paper-tube-making machines, comprising a tube split longitudinally, and a flat strip located in said tube and movable longitudinally therein, one of the parts having a spiral groove and the other a pin engaging said groove.

26. An arbor for paper-tube-making machines, comprising a tube split longitudinally, and a flat strip rotatable therein; in combination, with a reciprocating bearing for the arbor, and means for turning the strip as the arbor reciprocates, substantially as shown and described.

27. In a machine for making paper tubes, the combination, of a hollow arbor split longitudinally, a reciprocating bearing for the arbor, a flat strip extending through the arbor and provided with a spiral groove, a pin on the arbor engaging said groove, and a fixture imparting a longitudinal movement to the strip as the arbor reciprocates, substantially as shown and described.

28. In a machine for making paper tubes, the combination, of a hollow arbor split longitudinally, a reciprocating bearing for the arbor, a flat strip extending through the arbor and provided with a shank having a spiral groove, a pin on the arbor engaging said groove, and a depending arm or bracket having an inclined slot, the end of the strip engaging said slot, substantially as shown and for the purpose set forth.

29. In a machine for making paper tubes, the combination, of a pan or receptacle containing paste, an arbor, a vertically-movable bearing in which said arbor is supported, gearing mechanism meshing with the arbor when the latter is in its lowermost position, and a tube-ejector slidable upon said arbor, substantially as shown and described.

30. In a machine for making paper tubes, the combination, of a pan or receptacle containing paste, an arbor, a vertically-movable bearing in which said arbor is supported, a movable plate carrying an arm engaging the free end of the arbor, and a tube-ejector slidably upon said arbor, substantially as shown and described.

31. In a machine for making paper tubes, the combination, of a pan or receptacle containing paste, an arbor, a vertically-movable bearing in which said arbor is supported, gearing mechanism meshing with the arbor when it is in its lowermost position, a folder movable against the arbor to fold the paper thereon, and a tube-ejector slidably longitudinally upon said arbor, substantially as shown and described.

32. In a machine for making paper tubes, the combination, of a pan or receptacle, an arbor, a vertically-movable bearing in which

said arbor is supported, gearing mechanism adapted to revolve the arbor, a tube-ejector slidable upon said arbor; together with slide-bars and gearing actuating the movable arbor-
5 support and reciprocating tube-ejector, and a cam-wheel actuating said slide-bars, substantially as shown and for the purpose set forth.

33. In a machine for making paper tubes, the combination, of a pan or receptacle, a plate pivoted therein, an arbor, a vertically-movable bearing in which said arbor is supported, gearing mechanism adapted to revolve the arbor, a tube-ejector slidable upon
10 the arbor, and a wiper or gasket disposed on a line with said arbor; together with slide-bars and interposed gearing actuating the movable arbor-support and reciprocating tube-ejector, and a cam-wheel actuating said slide-
15 bars, said cam-wheel having a lug which actuates the pivoted plate, substantially as shown and described.

34. In a machine for making paper tubes, the combination, of an arbor, a vertically-
20 movable support carrying said arbor, means for raising and lowering said support, a pinion at the outer end of said arbor, and a driven pinion adapted to mesh with the aforesaid pinion when the arbor is in its lower-
25 most position, substantially as shown and described.

35. In a machine for making paper tubes, the combination, of an arbor, a vertically-movable support carrying said arbor, means
30 for raising and lowering said support, a pinion on the arbor, and a driven pinion adapted to mesh with the aforesaid pinion when the arbor is in its lowermost position; together with a sleeve on the arbor, and means
35 for reciprocating said sleeve, substantially as shown and described.

36. In a machine for making paper tubes, the combination, of an arbor, a vertically-movable support carrying said arbor, means
40 for raising and lowering said support, a pinion on the arbor, and a driven pinion adapted to mesh with the aforesaid pinion when the arbor is in its lowermost position; together with a sleeve on the arbor, a reciprocating slide

adapted to engage the sleeve, and means for 50 reciprocating said slide, substantially as shown and described.

37. In a machine for making paper tubes, the combination, of an arbor, a vertically-movable support carrying said arbor, means 55 for raising and lowering said support, a pinion on the arbor, and a gear-wheel with which said pinion meshes when the arbor is in its lowermost position; together with a curved plate or former into which the arbor moves, substantially as shown and described.

38. In a machine for making paper tubes, the combination, of an arbor, a vertically-movable support carrying said arbor, means for raising and lowering said support, a pinion 60 on the arbor, and a gear-wheel with which said pinion meshes when the arbor is in its lowermost position; together with a pivoted plate adapted to fold over the arbor, substantially as shown and described.

39. In a machine for making paper tubes, the combination, of an arbor, a vertically-movable support carrying said arbor, means for raising and lowering said support, a pinion 65 on the arbor, and a gear-wheel with which said pinion meshes when the arbor is in its lowermost position; together with a curved plate or former into which the arbor moves, and a pivoted plate adapted to fold upon the arbor, substantially as shown and described.

40. In a machine for making paper tubes, the combination with a vertically-movable arbor upon which the paper is wound, of a curved plate or former into which the arbor moves and by which the paper is wrapped 85 around said arbor, substantially as described.

41. In a machine for making paper tubes, the combination, of a rotatable and vertically-movable arbor, a receptacle containing paste, and a curved plate or former in the bottom of 90 said receptacle, substantially as shown and described.

In testimony whereof I affix my signature in presence of two witnesses.

CHAS. A. BAILEY.
